UNITED STATES PATENT OFFICE

SAMUEL COOMBE, OF BROOKLYN, NEW YORK.

STONE TUB.

SPECIFICATION forming part of Letters Patent No. 391,121, dated October 16, 1888.

Application filed February 6, 1888. Serial No. 2nd3,111. (No model.)

To all whom it may concern:

Be it known that I, SAMUEL COOMBE, a citizen of the United States, residing at Brooklyn, in the county of Kings, State of New York, 5 have invented certain new and useful Improvements in Stone Tubs, Vats, Sinks, &c., of which the following is a specification, reference being had therein to the accompanying drawings.

10 This invention has relation to the manufacture of stone and other tubs, sinks, and vats, and among the objects in view are to reduce the labor generally expended thereon, reduce the cost of manufacture, and provide an article of the above character that will be stronger and less sensitive to the bad effects of heat and cold.

Other objects and advantages of the invention will hereinafter appear, and the novel features of the same will be particularly pointed out in the claims.

Referring to the drawings, Figure 1 is a perspective of a completed tub constructed in accordance with my invention. Fig. 2 is a similar view of the frame-work, the sides and bottom being removed. Fig. 3 is a detail in perspective of the corner-strip; and Fig. 4 is a horizontal section of one of the lower corners of the tub, and also illustrating a modification 30 of the joint.

Similar letters of reference indicate like parts in all the figures of the drawings.

A represents the sides of the tub, B the ends, and C the bottom, all of which are of 35 stone or other suitable substance, the same being fitted at their four corners by miter-joints D. (See Fig. 2.) If desired, however, the corner may be formed by a simple lap joint, as shown in Fig. 4; but the miter-joint is preferable.

The top and bottom of each of the corners are formed with a recessed portion, D', and seated therein, and adapted to embrace the sides and ends and project over the joints in 45 the corners, is a metallic L-shaped corner strip or binding, E, which is provided with perforations E² for bolts or screws. These corner-bindings, being in position and the tops thereof being seated within the recesses D', and there-

fore flush with the edge of the tub, serve to 50 firmly secure the vertical corner edges of the same together and form a tight joint.

Entirely surrounding the four lower edges of the tub is a metal binding-frame, F, formed with screw-holes F' and with offsets F² at each 55 corner, designed to embrace and form a seat for the lower ends of the corner binding-strips, E. This frame F may be made in sections or strips, or as a single piece, as shown, and serves the same purpose to the bottom, sides, and 60 ends as does the strip E to the side and ends—namely, it forms a rigid, durable, and tight joint, whereby the receptacle is prevented from unduly expanding by having hot or cold liquid poured therein. Tubs thus constructed 65 may be arranged in series, each being independent of the other, thereby obviating the liability of injury to one tub or the entire series by reason of liquid poured in another. Heretofore in the construction of these arti- 70

cles it required great expenditure of time and labor in forming the joints, which joints when formed were liable to soon become loose and worthless by reason of the expansion of the stone. By the construction herein described, 75 however, the time and labor is saved, and therefore the expense reduced and a far more durable and satisfactory joint formed.

Having described my invention and its operation, what I claim is—

1. The combination, with the sides, bottom, and ends of a stone tub or vat, of metallic corner-strips embracing the sides and ends thereof, and of a metallic frame-work embracing the four lower edges of the same and provided with offsets forming seats for the lower ends of the corner-strips, substantially as specified.

2. The combination, with the sides, bottom, and ends of a stone tub or vat, mitered at 90 their edges and recessed at their top and bottom corners, of metallic binding-strips embracing the side and end walls of the tub and seated in said recesses, and of a metallic frame-work embracing the sides, ends, and bottom 95 of the same and formed with offsets to receive the lower ends of the corner-strips, substantially as specified.

3. The combination of the sides, bottom, and ends A, C, and B, joined at D and recessed at D', with the L-shaped corner-strip E, secured to the corners and seated in the recesses, and 5 with the metallic frame-work F, formed with the offsets F', to receive the lower edges of the tub and form a seat for the strips E, substantially as specified.

In testimony whereof I affix my signature in presence of two witnesses.

SAMUEL COOMBE.
